(57) **CLAIM**

The ornamental design for a chair, as shown and described.

DESCRIPTION

FIG. 1 is a perspective view of a chair according to the present invention;

FIG. 2 is a front-elevational view of the chair of FIG. 1;

FIG. 3 is a side-elevational view of the chair of FIGS. 1 and 2, the other side view being a mirror image thereof;

FIG. 4 is a rear elevational view of the chair of FIGS. 1–3;

FIG. 5 is a top plan view of the chair of FIGS. 1–4; and,

FIG. 6 is a bottom view of the chair of FIGS. 1–5.

The broken lines shown in the Figures are for environmental purposes only and form no part of the claimed design.
